DESIGN FOR A DENTAL X-RAY FILM CASSETTE

Frank Forster Renwick, Gidea Park, England, assignor to Ilford Limited, Ilford, England, a British company

Application November 8, 1935, Serial No. 59,454
In Great Britain October 9, 1935

Term of patent 7 years

To all whom it may concern:

Be it known that I, Frank Forster Renwick, a subject of the King of England, residing at Lone Oak, 6, Reed Pond Walk, Gidea Park, Essex, England, have invented a new, original, and ornamental Design for a Dental X-Ray Film Cassette, of which the following is a specification, reference being had to the accompanying drawing, forming part thereof.

Figure 1 is a top plan view of the dental X-ray film cassette in opened position showing my new design;

Figure 2 is a side view thereof in opened position;

Figure 3 is a perspective view thereof in closed position; and

Figure 4 is a top plan view thereof in closed position, Figures 1, 2 and 4 being on the same scale and slightly larger than the perspective view shown in Figure 3.

I claim:

The ornamental design for a dental X-ray film cassette as shown and described.

FRANK FORSTER RENWICK.
